A. A. COURTNEY

CATTLE HORN WEIGHT

Filed Sept. 7, 1922

A. A. Courtney Inventor

By *C. A. Courtney*
Attorney

UNITED STATES PATENT OFFICE.

ARNOLD A. COURTNEY, OF OTTUMWA, IOWA.

CATTLE-HORN WEIGHT.

Application filed September 7, 1922. Serial No. 536,719.

To all whom it may concern:

Be it known that I, ARNOLD A. COURTNEY, a citizen of the United States, residing at Ottumwa, in the county of Wapello and State of Iowa, have invented a new and useful Cattle-Horn Weight, of which the following is a specification.

This invention relates to cattle horn weights and the object thereof is to provide a weight of this character so constructed that when properly applied is ever-tight and all danger of losing the weights avoided.

Another object is to so construct a device of this character that it will have a spring engagement with the animal's horn in addition to the set screw usually employed.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 represents a perspective view of the weight constituting this invention shown applied.

Fig. 2 is a horizontal section of the weight; and

Fig. 3 is a longitudinal section thereof.

In the embodiment illustrated the weight 1 which constitutes this invention is shown applied to a cow's horn H and is constructed of metal having sufficient weight to exert a bending tendency on the horn to which it is applied.

This weight 1 has a bore 2 extending longitudinally therethrough which tapers toward one end, the end having the small portion of the bore therein being thicker and designed to be positioned toward the end

of the horn. The other end of the weight is reduced in thickness and provided with longitudinally extending slots 4 which are here shown arranged diametrically opposite, although not necessarily so. This slotting of the weight provides spring clamping fingers 5 which assist in securing the weight to the horn. A set screw 3 extends transversely through the weight and is designed to engage the horn to assist the fingers in holding it securely connected to avoid all possibility of the weight being lost.

In the use of this device the weight is placed on the animal's horn with the set screw 3 located in the same direction in which it is desired to train the horn. The set screw is then turned about three sixteenths of an inch into the horn and the animal is then left in a barn or small lot for about twenty-four hours when the screw is again tightened. After the second tightening the animal may be turned out to pasture since all danger of the weight so secured being lost is minimized.

I claim:

1. A horn weight for cattle having a longitudinally extending bore and a slot opening through one end thereof.

2. A horn weight for cattle having a longitudinally extending bore and slotted longitudinally at one end to form spring gripping fingers.

3. A horn weight for cattle having a longitudinally extending bore, the walls thereof tapering in thickness toward one end, said tapering end being provided with a plurality of longitudinally extending slots to form spring gripping fingers.

In testimony that I claim the foregoing as my own, I have hereto affixed my signature in the presence of two witnesses.

ARNOLD A. COURTNEY.
